UNITED STATES PATENT OFFICE.

JOHN H. FITZGIBBON, OF ST. LOUIS, MISSOURI.

IMPROVEMENT IN PHOTOGRAPH-MOUNTS.

Specification forming part of Letters Patent No. 148,201, dated March 3, 1874; application filed May 24, 1873.

To all whom it may concern:

Be it known that I, JOHN H. FITZGIBBON, of St. Louis, in the county of St. Louis and in the State of Missouri, have invented certain new and useful Improvements in Mount for Photographs, Gems, Ferrotypes, and Pictures; and do hereby declare that the following is a full, clear, and exact description thereof, reference being had to the accompanying drawings, and to the letters of reference marked thereon, making a part of this specification.

My present invention is intended as an improvement on the Letters Patent No. 131,260, granted to me for picture mounts or mats; and it consists in a flap or cover for the front and back of the picture, attached to or made part of the mount without any adhesive material on such cover or flap, for the purpose of protecting the picture, when mounted, from injury.

In order to enable others skilled in the art to which my invention appertains to make and use the same, I will now proceed to describe its construction and operation, referring to the annexed drawing, which represents a perspective view of my improved picture mount or mat.

A represents an ordinary mat or mount for gem or other pictures. The back of this mount is either wholly or partially covered with gum, mucilage, or other adhesive material.

By this means the picture can, if so de-

sired, first be stuck to the back of the mount, and then the cover or flap B fastened on to hold the picture in place on the mount, without the use of any mucilage or any other adhesive material on said cover or flap. This not only saves time and labor, but prevents any liability of spoiling the picture by the gum.

C represents the front flap. The flaps B and C are made of one piece, the mount A being secured at the center of the piece, as shown.

This construction obviates the necessity of using any adhesive substance on either the front or back flap, as the picture is secured by the mucilage on the back of the mount, and protected on its back by the flap B, and the front covered by the loose flap C.

Having thus fully described my invention, what I claim as new, and desire to secure by Letters Patent, is—

The within-described picture-mount, consisting of the part A, with adhesive substance on its back, and attached at one end to the center of a piece of paper, which forms the back B, and the front flap C, all as shown and described, and for the purpose set forth.

In testimony that I claim the foregoing I have hereunto set my hand this 24th day of April, 1873.

JOHN H. FITZGIBBON.
